UNITED STATES PATENT OFFICE.

NICHOLAS A. BECKER, OF SOUTH SAN FRANCISCO, CALIFORNIA.

CURB-BAR.

1,221,955.

Specification of Letters Patent.

Patented Apr. 10, 1917.

Application filed August 28, 1915, Serial No. 47,777. Renewed February 19, 1917. Serial No. 149,654.

To all whom it may concern:

Be it known that I, NICHOLAS A. BECKER, a citizen of the United States, residing at South San Francisco, in the county of San Mateo and State of California, have invented certain new and useful Improvements in Curb-Bars, of which the following is a specification.

The present invention relates broadly to 10 protecting structures for corners, edges and the like of cement or other composite work.

The object of my invention is to provide a simple, inexpensive and efficient protector or guard for use in connection with cement 15 work and one particularly designed to be employed in connection with cement or concrete street curbings to protect the exposed corners and face thereof from being chipped or broken by sudden shocks; to provide a 20 structure which when positioned will protect a slight distance over the top and side faces of the curb and the corners thereof and thereby protect the same from becoming chipped or broken; to provide one which 25 is thickened or formed with a reinforcement adjacent its corner curved section where the heaviest shocks or greatest wear occurs; and to provide one with means for preventing the overhang of the vehicle tires from contacting with the side face of the curb below 30 the protecting guard, thereby protecting the face of the curb from injury or wear due to the action of the vehicle tires.

With the above mentioned and other objects in view the invention consists in the novel construction and combination of parts hereinafter described and illustrated in the accompanying drawings; it being understood that various changes in the form, proportion, and minor details of construction 40 may be resorted to without departing from the spirit or sacrificing any of the advantages of the invention.

To more fully comprehend the invention, 45 reference is directed to the accompanying drawings, wherein—

Figure 1 is a view in section of a curb with an embodiment of my invention applied thereto.

Fig. 2 is a transverse sectional view of a 50 slightly modified form of device.

Referring more particularly to the drawings, the numeral 1 is used to indicate a suitable curbing formed preferably of con-

crete or cement and having the top and side 55 faces 2 and 3.

In Fig. 1 of the drawings, the improved guard is illustrated as embedded in the curbing at the corner thereof, with its outer surface adjacent its side edges flush with 60 the outer surface of the curb and the guard or protecting structure is shaped by any suitable process and from any suitable material, and said guard comprises a body member 4 shaped as a straight section for protecting the front wall surface of the curb and adapted when positioned to extend downwardly from the corner edge of the said curb over a portion of the vertical side 65 wall 3 thereof, said member 4 is provided with an upwardly and inwardly curved head 70 or member 5 which is adapted to extend over the corner of the curb and the same when positioned extends a slight distance inwardly 70 on the upper horizontal surface 2 of the 75 said curb.

An outwardly projected or thickened portion 6 of the head 5 extends longitudinally of the guard, and the same is positioned intermediate the edges thereof and preferably 80 at the curvature of the member 5 relative to the member 4 so as to resist the heavy shocks or blows which would normally strike the corner of the curb. The outwardly projecting or thickened portion 6 overhangs the 85 outer face of the straight side wall or member 4 and prevents the overhanging or projecting edges of the vehicle tire from contacting with the vertical side wall surface of the curb below the guard positioned with- 90 in the curbing.

The guard or protecting structure is anchored in position by the anchoring bar 7 which extends substantially horizontally into the curb and projects inwardly from the 95 inner surface of the straight side wall or member 4 at right angles thereto. The said anchor bar is provided at its outer end with an enlarged head 8 and is passed through a suitable opening 9 formed in the straight 100 side wall or member 4 of the curb guard and the anchor bar is curved at its inner end, as at 10, and the curvature thereof prevents the withdrawal of the same from its embedded position after the concrete or 105 cement forming the curb hardens or sets.

By the employment of my improved guard, the corner of the curb and the side

- and top faces thereof adjacent the corners is protected from injury, and the outwardly extended or thickened portion 6 projected beyond the face of the head member 5 of the guard reinforces the same at the point where the same is subjected to the greatest shocks and strains, and the same prevents the injury of the curb below the guard by the overhang of the vehicle tires. It is apparent that by projecting the anchor bar 7 inwardly at substantially right angles to the vertical portion of the protecting guard member 4, and extending the same substantially horizontally into the curb, that all shocks or strains received by the guard or protecting structure are not transmitted longitudinally of the anchor, and which when so transmitted tend to split the cement forming the curb, as is the case with the present form of anchor means for the curb guards, but such shocks or strains are received transversely of the anchor and the transmission thereof in no manner injures the composite curb.
- In the modified form of device disclosed in Fig. 2 of the drawings, the anchor bar is threaded into the body member 4 as at 11, and the inner face of the said body member 4 and the head member 5 of the protecting guard structure is grooved longitudinally as at 12 to provide channels to receive the con-

crete or cement of the curb and serve as a further anchoring means for the curb guard structure.

Having thus described my invention, what I claim is:—

A rolled metallic protecting guard for composite structures comprising a straight wall or body member for protecting the front wall surface of the structure, an enlarged upwardly projected inwardly curved head member formed integral with the body member for overlying the corner edge and top wall surface of the composite structure, said head member being of greater thickness than the body member and said increased thickness providing an overhanging section projected outwardly beyond the face of the front wall or body member of the guard, and an anchor detachably secured to and extended transversely through the body member of the guard for positioning within the structure to be protected and to lie in a plane parallel with the top wall surface thereof.

In testimony whereof I have signed my name to this specification in the presence of two subscribing witnesses.

NICHOLAS A. BECKER.
